UNITED STATES PATENT OFFICE.

JOHN J. HICKEY, OF BROOKLYN, NEW YORK.

DESIGN FOR A CHRISTMAS-CLUB SAVING STAMP.

Application filed June 21, 1924. Serial No. 9,941. Term of patent 14 years.

To all whom it may concern:

Be it known that I, JOHN J. HICKEY, a citizen of the United States, residing at Brooklyn, in the county of Kings and State of New York, have invented a new, original, and ornamental Design for Christmas Club Saving Stamp, of which the following is a specification, reference being had to the accompanying drawing, forming part thereof.

The drawing illustrates a plan view of a stamp designed in accordance with this invention.

I claim:

The ornamental design for a Christmas club saving stamp, as shown.

JOHN J. HICKEY.
